COMBINATION TOOL

Warren Frederick Flesselles, Potts Point, near
Sydney, New South Wales, AustraliaApplication March 14, 1934, Serial No. 715,542
In Australia April 7, 1933

1 Claim. (Cl. 33—112)

This invention relates to an improved combination tool devised principally for use by engineers.

The main object of the invention is to provide a ready and accurate means of centering 5 rectangular and substantially rectangular bodies such as bars of metal with flat surfaces.

The invention is intended also to function as a set square and will be found very useful for many kindred purposes.

10 According to the invention I provide a graduated bar or blade after the nature of a steel rule and securely mount upon one end thereof an abutment disposed at right angles to the said bar and projecting above or below the face thereof 15 as in the form of a T or set square.

The graduated bar is provided with orifices in the form of diagonal slots preferably disposed at an angle of 45° and parallel to one another. The orifices, which are numbered, are disposed 20 preferably throughout the length of the graduated bar portion, the main object of these being to enable the tool to be used for centering work, but they also enable it to be used as a gauge by placing a pencil or scriber in a particular hole 25 and using the abutment as a stop against the edge of the work.

In order that the invention may be more readily understood reference will now be made to the accompanying drawing, wherein:—

30 Figure 1 is a plan view illustrating the invention.

Figure 2 is a detail view showing the first step in using the invention to centre a piece of work.

35 Figure 3 is a detail view showing the piece of work inscribed after the operation shown in Figure 2.

Figure 4 is a detail view showing the second step in using the invention to centre a piece of work; in this view it will be noted that the position of the tool has been reversed to that shown 40 in Figure 2.

Figure 5 is a detail view showing the piece of work inscribed by a diagonal line in two planes the intersection of which represents the 45 centre point of the width of the work.

The bar 20 which may be graduated in units 50 of linear measurement is provided with orifices in the form of diagonal slots 21 each of which is numbered, there being nineteen slots shown in Figure 1.

An abutment 23 is secured in known manner,

for instance by a screw 24, to the bar or blade 20 and enables the tool to be used as an ordinary square.

In use as a centre marker the tool is placed upon the work 25 with the fixed abutment 23 against one face thereof, the approximate width of the work is then noted upon the graduated scale and the measurement divided by two which roughly gives the position of the centre of the work 25.

10 The particular diagonal orifice 21, which falls upon the approximate centre, is then noted by its numbers 1 to 19 and a datum line 26 is scribed upon the work 25 at right angles to the fixed abutment 23 say by means of the lower edge of the blade 20; or the position of the blade may be 15 retained by the point of the scriber; also a diagonal line 27 is scribed upon the work 25 with the aid of the selected orifice 21 as a guide leaving the work as shown in Figure 3.

20 The second operation (see Figure 4) is to place the tool on the right hand side of the work 25 with the reverse side face down upon the work and the lower edge of the blade 20 on the datum line 26 or in engagement with the scriber as before and then scribe a second diagonal line 28 with the 25 same orifice 21 as a guide.

The work will then have the appearance shown in Figure 5 and the intersection of the two diagonal lines 27 and 28 will be found to be the correct centre of the work 25 in that particular 30 plane.

It will be appreciated that various modifications may be made without departing from the spirit of the invention as defined by the appended 35 claim.

I claim.

An improved combination tool for centering rectangular and substantially rectangular bodies such as bars of metal, comprising a blade having 40 therein a plurality of closely disposed diagonal orifices or slots preferably arranged at an angle of 45° to the edges of said blade and parallel to each other; said blade having numerals arranged 45 in sequence on both of its faces and adjacent to said orifices or slots, and said blade having thereon graduations indicating units of linear measurement; and an abutment securely mounted upon one end of said blade, said abutment being disposed at right angles with respect to the edges of said blade.

50 WARREN FREDERICK FLESSELLES.
